UNITED STATES PATENT OFFICE.

THOMAS E. LANDER AND JOHN HAUENSTEIN, OF KANSAS CITY, MISSOURI.

FLASH-LIGHT.

1,363,132.

Specification of Letters Patent. Patented Dec. 21, 1920.

Application filed January 2, 1920. Serial No. 348,863.

To all whom it may concern:

Be it known that we, THOMAS E. LANDER and JOHN HAUENSTEIN, citizens of the United States, residing at Kansas City, in the county of Jackson and State of Missouri, have invented certain new and useful Improvements in Flash-Lights, of which the following is a specification.

Our invention relates to flash lights and 10 pertains more particularly to attachments for holding one or more flash lights, and for signaling and other purposes.

The invention may be employed to advantage by automobile drivers, crossing 15 policemen, railroad men, and others having occasion to signal at night or use flash lights for other purposes, and in order that said invention may be fully understood, reference will now be had to the accompanying 20 drawings, in which:

Figure 1 is a plan view of a pair of flash lights equipped with the invention.

Fig. 2 is a rear elevation of the parts disclosed by Fig. 1.

25 Fig. 3 is a side elevation partly in section of the parts disclosed by Figs. 1 and 2.

Fig. 4 is a detail of an arm and a signal lens associated with said arm.

Referring now in detail to the various 30 parts, A designates a pair of flash lights of usual or any preferred construction. Each flash light A is provided at its forward end with a lens B and at its rear end with a screw cap C, which latter is removable so 35 that the usual battery may be placed within the cylindrical body portion D of the flash light. Each flash light is also equipped with the customary switch F.

Referring now more particularly to the 40 device constituting the present invention, 2 designates a handle provided at its ends with oppositely-disposed clamp members 4 adapted to embrace the cylindrical body 45 portions D of the flash lights A and reliably hold the same.

One side of the handle 2 is provided with a stationary sheath 6 in which arms 8 and 9 are slidably and removably mounted. Each arm has a resilient tongue 12 struck therefrom as shown on Fig. 4, to hold it in frictional engagement with the interior of the 50 sheath 6. The arms 8 and 9 are connected at their outer ends by hinges 14 and 16 to annuli 18 and 20, adapted to engage the

front ends of the flash lights A and provided with spring clips 22 and 24, respectively, which grasp the heads of the flash lights and coact with the arms 8 and 9 in holding said annuli in place. The annuli 18 and 20 are provided with lenses 26 and 28, respectively, the lens 26 being, preferably, red, while the lens 28 is, preferably, green or some other suitable color so that said lenses may be employed for signaling purposes.

The stationary sheath 6 is provided with a movable sheath 30 connected to said stationary sheath 6 by a hinge 32. The movable sheath 30 is equipped with a blade 34, which is slidable within the sheath 30, so 70 that it may be partly withdrawn from said sheath as disclosed on Fig. 3. The hinge 32 is friction-tight in order to hold the sheath 30 downwardly against the stationary sheath 6, or in the position disclosed by 75 Fig. 3, or in any intermediate position. However, a catch 36 secured to the stationary sheath 6, is employed to reliably hold the movable sheath 30 downwardly against said stationary sheath 6.

In practice, when a powerful white light is desired, such as when repairing an automobile at night or changing a tire, the annuli 18 and 20 are swung on the hinges 14 and 16 to throw the colored lenses 26 and 28, respectively, from in front of the lenses B. If preferred, the entire device may be supported by grasping the handle 2 with one hand, but if the use of both hands is desired for other work, the movable 90 sheath 30 is swung downwardly and the blade 34 is partly withdrawn and inserted in the ground for support. The flash lights may then be adjusted to any desired angle through the intermediacy of the friction hinge 32, to throw the light to the desired 95 point.

When the device is to be used for signaling purposes, one of the flash lights A is reversed, together with one of the colored 100 lenses, and its supporting arm, as indicated by dotted lines on Fig. 1. Thus should the lamp circuit of an automobile get out of order at night, the red lens may be utilized as a tail light to guard against rear end 105 collisions, while the lens B of the companion flash light can be used as a head light in illuminating the road ahead.

From the foregoing description it will be understood that we have provided an attachment whereby the usefulness of flash lights is greatly increased and while we have disclosed the preferred embodiment of our invention, we reserve the right to make such changes in the construction, combination and arrangement of parts as properly fall within the spirit and scope of the appended claims.

Having thus described our invention, what we claim and desire to secure by Letters Patent, is:

1. In a device of the character described, a handle, clamp members secured to said handle and adapted to support a flash light, and a colored lens associated with said handle and adapted to cover the flash light lens.
2. In a device of the character described, a handle, clamp members secured to said handle and adapted to support a flash light, and a blade associated with the handle and adapted to support the same.
3. In a device of the character described, a handle, clamp members secured to said handle and adapted to support a flash light, an annulus adapted to embrace the front end of said flash light, a colored lens fitted to said annulus, and an arm associated with

the handle and having a hinge connection with the annulus.

4. In a device of the character described, a handle, clamp members secured to said handle and adapted to support a flash light, an annulus adapted to embrace the front end of said flash light, a colored lens fitted to said annulus, an arm to which the annulus is hinged, and a sheath on the handle to receive said arm.

5. In a device of the character described, a handle, clamp members secured to said handle and adapted to support a pair of flash lights, annuli provided with lenses and adapted to embrace the front ends of said flash lights, a pair of arms to which said annuli are operably-connected, a sheath fixed to the handle and in which said arms are removably mounted, a second sheath operably-connected to the first sheath, and a blade slidably mounted on said second sheath, for the purpose described.

In testimony whereof we affix our signatures, in the presence of two witnesses.

THOMAS E. LANDER.
JOHN HAUENSTEIN.
